UNITED STATES PATENT OFFICE

151,449

DESIGN FOR A COMBINED COASTER AND
ASH TRAY

William E. Jenkins, Sierra Madre, Calif.

Application November 12, 1946, Serial No. 134,713

Term of patent 7 years

(Cl. D44—10)

To all whom it may concern:

Be it known that I, William E. Jenkins, a citizen of the United States, residing at Sierra Madre in the county of Los Angeles and State of California, have invented a new, original, and ornamental Design for a Combined Coaster and Ash Tray, of which the following is a specification, reference being had to the accompanying drawings forming a part thereof.

Figure 1 is a plan view of a combined coaster and ash tray, showing my new design.

Figure 2 is a sectional view taken along the line 2—2 of Figure 1.

I claim:

The ornamental design for a Combined Coaster and ash tray, as shown.

WILLIAM E. JENKINS.
